CLIP FOR PICTURE FRAMES

Samuel Wiener, Jr., Westport, Conn.
(451 W. Broadway, New York, N.Y. 10012)

Filed Feb. 8, 1974, Ser. No. 440,668

Term of patent 14 years

Int. Cl. D8—08

U.S. Cl. D8—257

FIG. 4

FIG. 3

FIG. 2

FIG. 5

FIG. 6

FIG. 1

FIG. 1 is a view in perspective of a clip for picture frames showing my new design;

FIG. 2 is a side elevational view thereof, the opposite side being symmetrical;

FIG. 3 is a rear elevational view thereof;

FIG. 4 is a front elevational view thereof;

FIG. 5 is a bottom plan view thereof; and

FIG. 6 is a top plan view thereof.

I claim:

The ornamental design for a clip for picture frames, substantially as shown and described.
